(57) **CLAIM**

The ornamental design for a throw-away tip for metal cutting tool, as shown and described.

DESCRIPTION

FIG. 1 is a front view of a first embodiment of a throw-away tip for metal cutting tool showing our new design,

FIG. 2 is a rear view thereof;

FIG. 3 is a top view thereof;

FIG. 4 is a bottom view thereof;

FIG. 5 is a right side view thereof;

FIG. 6 is a left side view thereof;

FIG. 7 is a first perspective view thereof;

(Continued)

FIG. 8 is a second perspective view thereof;
 FIG. 9 is a referential top view thereof;
 FIG. 10 is a cross sectional view taken along line 10-10 of FIG. 9; and,
 FIG. 11 is a cross sectional view taken along line 11-11 of FIG. 9.

1 Claim, 5 Drawing Sheets
